CLAIM

The ornamental design for a wire tote basket, as shown and described.

DESCRIPTION

FIG. 1 is a perspective view of a wire tote basket in accordance with my design;

FIG. 2 is a top plan view thereof;

FIG. 3 is a front elevational view thereof, with the rear elevational view being substantially identical;

FIG. 4 is left side view thereof with the right side view being substantially identical; and,

FIG. 5 is a bottom plan view.
